UNITED STATES PATENT OFFICE

2,611,589

APPARATUS FOR COMPACTING A REFRAC-
TORY MEDIUM IN A BUNG OF CHINAWARERichard Henry Pass and Walter A. Johnson,
Syracuse, N. Y., assignors to Onondaga Pottery
Company, Syracuse, N. Y., a corporation of New
York

Application December 20, 1950, Serial No. 201,822

9 Claims. (Cl. 259—72)

1

This invention relates to apparatus for embedding stacks or bungs of unfired ceramic ware, such as plates, saucers, and the like, with a loose compactible clay refractory material, and more particularly this invention has to do with a modified structural arrangement of the apparatus disclosed in the co-pending application of Richard H. Pass, Sr. No. 201,407, filed December 18, 1950.

The invention consists in the novel features and in the combinations and constructions hereinafter set forth and claimed.

In describing this invention, reference is had to the accompanying drawings in which like characters designate corresponding parts in all the views.

Figure 1 is a front elevational view of an apparatus embodying our invention.

Figure 2 is a top plan view.

Figure 3 is a view taken on line 3—3, Figure 1.

Figure 4 is a vertical sectional view of the structure as shown in Figure 1.

Figure 5 is an inverted view taken on line 5—5, Figure 1.

Figure 6 is a view taken on line 6—6, Figure 4.

Figure 7 is a view taken on line 7—7, Figure 6.

Figure 8 is a view taken on line 8—8, Figure 7.

Figure 9 is a view taken on line 9—9, Figure 7.

Figure 10 is a view taken on line 10—10, Figure 4.

The apparatus includes a frame having four vertically extending post members 20, to the upper ends of which there is secured a rectangular top member formed of channel elements 21. Cross members 22 are secured adjacent the lower ends of the leg members 20, and cross members 23 are mounted in the leg members intermediate the ends thereof. A hopper 24 is supported by three brace members 25 extending upwardly from the channel elements 21. The pair of these members 25, arranged on the forward and rear sides of the apparatus, are connected at their upper ends with a plate 26 extending transversely across the top of the hopper 24. The hopper has a cylindrical chute 28 depending therefrom, the lower end of which is encircled by a second cylindrical chute 29 supported, as by screws 30 depending from a pair of cross members 31 mounted on the channel elements 21 and extending diagonally across the corner portions thereof, as shown in Figures 2 and 3, the screws 30 being mounted in a ring member 33 fixed to the under side of the supports 31, the screws being provided with adjusting nuts whereby the lower chute 29 can be adjusted toward and from the upper chute 28.

2

The bung of ware is supported on a disk 35 secured to the upper end of a piston rod 36 extending upwardly from a cylinder 37 mounted upon an upright 38 extending between the lower and intermediate cross members 22, 23, see Figure 1. By means of this piston and cylinder arrangement, the bung support 35 is moved vertically toward and from the chutes 28, 29, and the support is arranged coaxially therewith.

The refractory material is compacted between the rims of the pieces of ware of the bung by a cylindrical casing 40, known as a coddle, carried by mechanism depending from a carriage 41 provided with a plurality of rollers 42 mounted upon an annular track member 43 secured to the under sides of the channel elements 21, see Figures 2, 3 and 4. The rollers 42 are journaled on studs 45 mounted in vertically extending flange members 46 welded or otherwise secured at points circumferentially spaced about the periphery of the carriage 41 which is formed with a large central aperture to permit free rotation of the carriage on the track 43 about the lower chute 29. A gear reduction motor 47 is mounted upon an angle member 48 secured to the channels 21 of the top frame member adjacent one corner thereof, see Figures 2 and 3. The output shaft from the gear reduction motor depends from the unit and has affixed to its lower end a sprocket 50. A ring 51, formed of insulating material, is fixed to the carriage 41, as by screws 52, and is positioned to encircle the lower chute 29, the screws 52 also serving to attach a sprocket 54 to the member 51, and a drive chain 55 is trained about the sprockets 50, 54. This provides power means for effecting rotation of the carriage about the axis of a bung of ware positioned upon the support 35.

The casing 40 is connected at its opposite side portions to and supported by motion transmitting or actuating members 56 pivotally mounted at their upper ends in bifurcated brackets 57 secured to the under side of the carriage disk 41 as by pins 58, see Figure 6. The lower end portions of the members 56 are formed with relatively wide slots, the opposing vertical walls of which are provided with wear plates 60 to receive the outer race of an anti-friction bearing 61, see Figure 7. This bearing is mounted on a sleeve 62 having an eccentrically arranged bore to receive a shaft 63. The sleeve 62 is formed with an enlarged collar portion 64 formed with a radial slot 65 and a clamp screw 66, Figure 9. The end portion of the shaft 63, on which sleeve 62 is mounted, has its periphery eccentric to its axis. Accordingly the eccentricity of the sleeve 62 and bearing

61 carried thereon, can be adjusted by rotating the eccentric sleeve 62 on the eccentric portion of shaft 63 and then fixedly secure the sleeve to the shaft by the clamp screw 66, as will be apparent from Figures 7 and 9.

The shafts 63 are journaled intermediate their ends in bearings 68 mounted in housings 69 supported by channel members 70 depending from the under side of the carriage 41. The ends of the shafts 63, on which the sleeves 62 are mounted, are fastened to shafts 72 of motors 73, as by pins 74. The motors 73 are, in turn, mounted upon a pair of channel members 75 depending from the under side of the carriage 41. During rotation of the carriage 41 about its vertical axis, the motors 73 are supplied with power from collector rings 76 mounted upon the insulating ring 51 and supplied with current by branches not shown.

The casing 40 is provided on opposite sides with radially extending flange members 77, these members being spaced apart to receive the actuating members 56. The flanges 77 have affixed to their inner confronting faces, plates 78. These plates and the flanges 77 are formed with elongated vertically extending slots 79 to receive bolts 80. The members 56 are apertured to receive a bearing bushing 81 in which is mounted a spacing sleeve 82 and through which the bolt 80 extends, and which forms a spacer between the plates 78 so that the bolt may be tightened by nut 83, Figure 7.

With this arrangement, the casing 40 is supported by the members 56, and the casing may be adjusted vertically so that the force exerted by the eccentric mechanism to effect reciprocation of opposite sides of the casing may be applied at different points vertically along the casing. The adjustment of the eccentricity of the members 62 provides for variation in the amplitude of the reciprocation of the casing.

The refractory clay material is fed to the hopper 24 by any suitable means as the conveyor belt 86, Figure 4. This belt is trained over a pulley 87 journaled on the conveyor frame 88 and is located within the hopper 24. The pulley 87 is intermittently rotated in the direction of the arrow 90 by a motor, not shown, whereby the clay refractory material, carried by the upper run of the belt 86, is deposited into the hopper 24 from whence it descends through the chutes 28, 29, and is directed in the annular space between the bung of ware and the casing 40 by a conical member 92 secured to a tubular member 93 slidably mounted in a spider member 94 mounted in the lower end of the chute 28 and in a guide bearing 95 mounted in the transverse member 26. A member 96 formed of yieldable material, such as sponge rubber, is fixed to the base of the conical member 92.

In operation, a bung of ware is placed upon the support 35, fluid pressure is applied to the lower end of the cylinder 37, causing the support to move upwardly and position the bung within the casing 40. During this upward movement, the topmost plate in the stack of the bung is engaged by the member 96 and the conical member 92 is moved upwardly to the position shown in Figure 4. The upward movement of the support 35 is controlled by a stop in the nature of a chain 98, the ends of which are secured to the cylinder 37 and the support 35. At the end of the upward stroke of the support, a switch is actuated by a pin 99 secured to the support 35, the pin engaging a switch actuator 100. This switch closes a

circuit to the actuating motor for the conveyor 86 whereupon a quantity of the clay refractory material is deposited in the hopper 24 and descends about the bung of ware in the casing. As the clay material is discharged between the bung and the casing 40, opposite side portions of the casing are reciprocated by the eccentric mechanisms connected to the motors 73 and simultaneously, the carriage 41 is rotated about the axis of the track 43 by the motor 47. The lower chute 29 may be provided with one or more window openings 102 so that the operator may observe when the bedding material has been supplied in sufficient quantity to effect embedding of the bung, whereupon the power supply to the conveyor is opened manually, and the support 35 lowered to permit removal of the embedded bung. Upon downward movement of the support 35, the bung of ware is lowered from the casing 40, the conical member 92 and the resilient member 93 following the bedded bung of ware downwardly. The stem 93 is provided with stop collars 104 to limit downward movement of the members 92, 93, when the same reach a position at the bottom of the casing 40. The motors 47, 73 may be operated continuously, or may be stopped and started for the bedding operation of each bung of ware.

Preferably, the casing 40 is formed of thin sheet resilient material, such as steel, and the reciprocation is such that opposite side portions of the casing are simultaneously moved inwardly and outwardly. In order that the eccentric mechanisms may thus operate in synchronism, the sprockets 105 are affixed to the outer ends of the shafts 63 and are connected by means of a roller chain 106.

What we claim is:

1. Apparatus for compacting a loose refractory clay medium between the rims of pieces of green chinaware arranged in a bung comprising a suitable frame, a support for the bung, a non-rotatable casing encircling said bung in spaced relation thereto to receive a quantity of said refractory clay between the bung and the casing, means operable to effect opposed reciprocation of opposite side portions of said casing radially toward and from the axis of said bung, and means operable to effect rotation of said casing about the axis of said bung during such reciprocation.

2. Apparatus for compacting a loose refractory clay medium between the rims of pieces of green chinaware arranged in a bung comprising a suitable frame, a non-rotatable support for the bung of ware, a cylindrical casing arranged concentric of the bung and mounted in the frame for rotation about the axis of the bung and being spaced therefrom to receive a quantity of said clay refractory medium between the bung and the casing, motion transmitting means detachably connected to opposite side portions of the casing and operable to simultaneously reciprocate said portions radially toward and from the axis of the bung, and means operable to effect rotation of said casing during such reciprocation.

3. Apparatus for compacting a loose refractory clay medium between the rims of pieces of green chinaware arranged in a bung comprising a suitable frame, a non-rotatable support for a bung of ware, a cylindrical casing encircling the bung in spaced relation thereto to receive a quantity of said refractory material, power operated means rotatable with said casing and operable to reciprocate opposite side portions of the casing toward and from the axis of the bung,

and means operable to effect rotation of said casing during such reciprocation.

4. Apparatus for compacting a loose refractory clay medium between the rims of pieces of green chinaware arranged in a bung comprising a frame, an annular track mounted in the frame, a carriage supported by said track and being movable thereon about the axis of the track, a cylindrical casing depending from said carriage, a non-rotatable support operable to support a bung of ware within said casing, means for directing a quantity of said clay refractory material within the casing, power operated means supported by said carriage and being operable to effect reciprocation of opposite side portions of the casing toward and from the axis of the bung, and means operable to effect rotation of said carriage during such reciprocation.

5. Apparatus for compacting a loose refractory clay medium between the rims of pieces of green chinaware arranged in a bung comprising a frame, an annular track mounted on the frame, a carriage suspended from said track and mounted for rotation thereon about the axis thereof, a cylindrical casing formed of resilient material depending from said carriage, a bung support mounted in the frame for vertical movement coaxially of the casing and being operable to position a bung of ware within said casing, means arranged to direct a quantity of said clay refractory within said casing, motor operated means supported from the carriage and being operable to effect reciprocation of opposite side portions of the casing toward and from the axis of the bung, and motor actuated means operable to effect rotation of said carriage about the axis of the bung.

6. Apparatus for compacting a loose refractory clay medium between the rims of pieces of green chinaware arranged in a bung comprising a frame, a nonrotatable support for the bung, a cylindrical casing formed of sheet resilient material encircling said bung in spaced relation thereto to receive a quantity of said refractory medium between the bung and the casing, means operable to effect reciprocation of opposite side portions of said casing radially toward and from the axis of said bung, and means operable to effect rotation of said casing during such reciprocation.

7. Apparatus for compacting a loose refractory clay medium comprising a frame, an annular track mounted on the frame, a carriage suspended from said track and mounted for rotation thereon about the axis thereof, a pair of casing supporting members pivotally mounted at like ends to said carriage and depending therefrom, a cylindrical casing secured at opposite sides to

said members, a bung support operable to position a bung of ware within said casing, power means mounted on said carriage and operable to effect oscillation of said casing supporting members about their pivots to effect reciprocation of said opposite side portions of the casing toward and from the axis of said bung, and power means operable to effect rotation of said carriage during oscillation of said casing supporting members.

8. Apparatus for compacting a loose refractory clay medium between the rims of pieces of green chinaware arranged in a bung comprising a frame, a vertically arranged cylindrical casing formed of resilient material, a support for the bung of ware mounted in the frame coaxially with said casing for vertical movement into and out of the casing, means operable to effect upward movement of said support to move a bung thereon within said casing, power means operable to effect reciprocation of opposite side portions of said casing radially toward and from the axis of the bung positioned therein, and means operable to effect relative rotation between said bung and casing during such reciprocation.

9. Apparatus for compacting a loose refractory clay medium between the rims of pieces of green chinaware arranged in a bung comprising a frame, a circular track mounted on the frame, a carriage suspended from said track and mounted for rotation thereon about the axis thereof, said carriage being formed with a central aperture, power operated actuating members depending from said carriage, an open-ended cylindrical casing supported by said members in coaxial relation to said aperture, a bung support mounted in the frame for vertical movement and being operable to move a bung of ware upwardly within said casing and to form a closure for the lower end thereof, means operable to dispense a quantity of said clay refractory material within said casing, motor operated means supported from said carriage and being operable to effect reciprocity of said actuating members toward and from the axis of the bung, and means operable to effect rotation of said carriage during such reciprocation.
